UNITED STATES PATENT OFFICE

161,575

PAIR OF VISORED SPECTACLES

Emeric Devay, New York, N. Y.

Application April 11, 1950, Serial No. 9,148

Term of patent 14 years

(Cl. D57—1)

To all whom it may concern:

Be it known that I, Emeric Devay, a citizen of the United States, residing at New York, in the county of New York and State of New York, have invented a new, original, and ornamental Design for Pair of Visored Spectacles, of which the following is a specification, reference being had to the accompanying drawing, forming part thereof.

In the drawing:

Fig. 1 is a fragmentary front elevational view of the pair of visored spectacles, showing my new design;

Fig. 2 is a top plan view thereof;

Fig. 3 is a section along the lines 3—3 of Fig. 1; and,

Fig. 4 is a section along the lines 4—4 of Fig. 1.

Part of the temples are shown in dotted lines merely for the purpose of better illustration.

I claim:

The ornamental design for a pair of visored spectacles, as shown and described.

EMERIC DEVAY.
